Primary Examiner—Stella M. Reid
Assistant Examiner—Shanda C Hill(57) **CLAIM**

The ornamental design for a blade dispenser, as shown and described.

DESCRIPTION

FIG. 1 is a front perspective view of the blade dispenser, showing the new design;

FIG. 2 is a front view of the blade dispenser;

FIG. 3 is a rear view of the blade dispenser;

FIG. 4 is a side view of the blade dispenser;

FIG. 5 is another side view of the blade dispenser;

FIG. 6 is a top view of the blade dispenser; and,

FIG. 7 is a bottom view of the blade dispenser.

The broken lines shown in the drawing disclosure are for illustrative purposes only and form no part of the claimed design.
